UNITED STATES PATENT OFFICE.

JOHN H. O'BRIEN, OF NASBY, SOUTH DAKOTA.

WHIM.

SPECIFICATION forming part of Letters Patent No. 662,292, dated November 20, 1900.

Application filed May 16, 1900. Serial No. 16,884. (No model.)

To all whom it may concern:

Be it known that I, JOHN H. O'BRIEN, a citizen of the United States, and a resident of Nasby, in the county of Lawrence and State 5 of South Dakota, have invented a new and Improved Whim, of which the following is a full, clear, and exact description.

The object of the invention is to provide a new and improved whim or miner's hoist, to 10 the end that the same may be operated with perfect control and freedom from accidents.

The invention consists in the novel features hereinafter particularly described, and defined in the claims.

15 Reference is to be had to the accompanying drawings, forming a part of this specification, in which similar characters of reference indicate corresponding parts in all the figures.

Figure 1 is a perspective view of a hoisting- 20 whim embodying my invention. Fig. 2 is a central vertical section, the tripod or frame at the mine-shaft being omitted. Fig. 3 is a plan view of the parts shown in Fig. 2, a fragment of the tripod being included; and Fig. 25 4 is an elevation of my improved bucket-hook, part of the hook being broken away.

The horizontal hoisting-drum A is operated by the sweep B, which has a suitable draft-tree b' for the horse and depending knees or 30 clutch-arms b, which enter openings a between the spokes a⁴ of the drum. The drum rotates around the vertical hollow standard or bearing c, rising from the frame C, the eye of the drum being bushed, as at a'. The sweep B 35 has a central pin B', which passes downward through the bearing c and rests on the short arm of a foot-lever D, said lever being housed by a boxing D' below the surface of the ground and having its outer end d inclined upward 40 to a height to be conveniently pressed upon by the foot of the operator, the weight of the sweep normally tending to press down the inner end of the lever and drop into engagement with the drum A. A latch E, pivoted 45 to a standard A² of the frame, is shouldered at e, Fig. 1, and is adapted to be swung over into engagement with the free end d of the lever D, and thus hold the sweep in the inoperative position at the will of the operator.

50 The hoisting-rope F passes from the drum over an idler a² on the frame and up over a second idler g on the ordinary tripod or frame

G at the mine-shaft, and at its lower end said rope carries a bucket-hook H for engaging the bail of the bucket I. The hook H is of novel 55 form to facilitate hitching on to and casting off the bucket, which latter is, as usual, dumped into a car (not shown) which is run beneath the bucket. The body or shank of the hook is secured at its upper end to the 60 rope and is formed of two spaced members H' H², and at the lower end of the body a tongue h' is pivoted to swing in the vertical plane. A sliding ring h² is adapted to be slipped downward over the tongue when the 65 latter is raised, and a spring-catch h³ holds the ring in the lowered position, the said catch having a bend h⁴ for engaging the ring and being bent outward at its free end, as at h⁵, for convenience of manipulation. The spring- 70 catch h³ may be pressed inward between the members H' H² in releasing the ring and tongue.

A brake-band J, secured to the frame at j, extends around the drum to a connection with 75 a brake-rod J', the brake-band having ears j', which rest on suitable blocks a³, which may be a part of the frame A. Thus the brake is maintained in position when slackened. The brake-rod J' is connected by links j² with the 80 brake-lever J², which is fulcrumed to the frame at j⁴ below the connection with the brake-rod J', and a plate j³ on the lever J² engages a ratcheted segment K for holding the 85 brake set.

In connection with the brake a safety device L is provided which may be thrown into engagement with the drum upon releasing the brake. Thus the safety device L is in the form of an elbow-lever, having a dog or toothed 90 head L' at the elbow, the short arm being fulcrumed to the frame at l' and the longer arm pivoted to the brake-rod J', the arrangement being such that an abnormal movement of the brake-rod in the direction to release the brake 95 will throw the toothed dog L' into engagement with the drum A and positively hold the drum against movement should the harness brake or the horse back up while the drum is relieved. The dog L' is slotted, as at l, 100 and adjustably secured by bolts l'. With this arrangement, including the hook H, the operator can control the hoist and dump and lower the bucket without backing up and

slackening the rope, which is necessary with ordinary hooks.

In operation the bucket is raised high enough to permit a car to be run under the bucket. The tender then depresses the foot-lever, thereby disengaging the sweep from the drum, and at the same time he puts the brake on hard. Then by keeping command of the brake the bucket is lowered onto the car, 10 and this done, without letting the rope slack, the brake-lever is locked with the brake applied, and the hook H is manipulated to cast off the bucket. The operator is now free to run the car out and empty the bucket, and 15 upon returning the car beneath the hook the bucket may be readily engaged by the hook H without slackening the rope. With the rope thus maintained free from slack the bucket can be swung clear of the car and will 20 hang plumb without the necessity of starting the horse to take up slack, as is the case where ordinary bucket-hooks are employed.

Having thus described my invention, I claim as new and desire to secure by Letters 25 Patent—

1. A hoisting apparatus comprising a frame, a drum, a hoisting-rope, a sweep de-

tachably engaging the drum, a foot-lever controlling the engagement between the sweep and drum, said lever extending to a point adjacent the depending end of the rope, a brake for the drum, a brake-rod terminating adjacent to the foot-lever, an elbow-lever pivoted to the brake-rod and fulcrumed on the frame, a dog carried by the lever and a brake-lever 35 for throwing the brake-rod.

2. The combination with a frame, of the drum, a brake-band encircling the drum, a rod extending from and connected with the brake-band, an operating-lever for said rod, 40 a lever fulcrumed on the frame and having an arm connected with the brake-rod, and an adjustable dog mounted on the lever and movable into engagement with the drum by an excessive releasing movement of the 45 brake.

In testimony whereof I have signed my name to this specification in the presence of two subscribing witnesses.

JOHN H. O'BRIEN.
